L. C. BAYLES ET AL

LUBRICATOR FOR ROCK DRILLS

Filed Aug. 12, 1924

UNITED STATES PATENT OFFICE.

LEWIS C. BAYLES AND FRED M. SLATER, OF EASTON, PENNSYLVANIA, ASSIGNEES TO
INGERSOLL-RAND COMPANY, OF JERSEY CITY, NEW JERSEY, A CORPORATION OF
NEW JERSEY.

LUBRICATOR FOR ROCK DRILLS.

Application filed August 12, 1924. Serial No. 731,540.

To all whom it may concern:

Be it known that we, LEWIS C. BAYLES and FRED M. SLATER, citizens of the United States, and residents of Easton, county of 5 Northampton, and State of Pennsylvania, have invented a certain Lubricator for Rock Drills, of which the following is a specification accompanied by drawings.

This invention relates to rock drills and 10 more particularly to devices for lubricating the air feed cylinders of stope drills.

Stope drills are usually provided with air feed cylinders which are supplied with air under pressure through the throttle 15 valve. The plunger which is adapted to operate in the feed cylinder is usually provided with packing or cup leathers to effect a fluid tight condition in the cylinder. In ordinary use, the plunger is subjected to 20 constant vibration due to the hammering of the hammer piston against the drill which causes excessive wear on the packing or cup leathers unless lubricant, such as oil, is supplied frequently thereto.

25 It is an object of this invention to supply lubrication in sufficient quantity to the cup leathers or packing in the feed cylinder to maintain them in good condition.

It is a further object of this invention to 30 supply lubricant from a common oil supply chamber which is provided for the accommodation of oil to be used for lubricating the hammer piston end of the rock drill and at the same time preventing communication between the air feed cylinder and the hammer cylinder. A device of this kind is desirable for the reason that if more than 35 one oiling chamber is provided in the rock drill, the operator is apt to neglect to fill 40 all of the chambers and the machine suffers from lack of lubrication.

Other objects and advantages of the invention will be in part obvious and in part pointed out hereinafter.

45 The drawing illustrates one embodiment which the invention may assume in practice and includes—

Figure 1, a side view of a stope drill equipped with a lubricator constructed in 50 accordance with the practice of the invention, parts being broken away to show the interior construction of the lubricator and the parts to which it is adapted to supply oil, and

Figure 2, an enlarged longitudinal section 55 of part of the stope drill showing the lubricator in one of its operative positions.

Referring to the drawing, the invention is illustrated in its application to a stope drill having a hammer cylinder A and an air 60 feed cylinder B joined in any suitable manner at a feed cylinder flange C. A hammer piston D is adapted to reciprocate within the hammer cylinder A to deliver blows to a drill steel E inserted in the front head F. 65 The drill steel E is held against the work by air under pressure introduced into the air cylinder B against a piston G provided with a suitable tail point (not shown). In order to prevent leakage from the feed cylinder B around the piston G there is provided suitable packing, as for instance, the cup leathers H.

In order to keep the cup leathers H soft and in good condition to maintain an air 75 tight joint in the cylinder B, it has been found desirable to inject small quantities of oil to the interior of the cylinder B. It has been found unsatisfactory to leave the lubrication of the feed cylinder to the judgment of the operator as either too much oil or not enough is adapted to be supplied, causing the leathers to deteriorate or wear out rapidly. Lubrication being necessary 80 for the proper operation of the hammer 85 piston as well as the air feed cylinder, it is proposed by this invention to employ a single oil reservoir J to supply lubricant to all of these parts. One difficulty in such an arrangement is that the air pressures existing 90 in the hammer cylinder and feed cylinder are not equal at all times and therefore, communication with the oil reservoir from both cylinders cannot be had at the same time without leakage of air from the 95 feed cylinder B to the hammer cylinder A which would result in carrying oil from one to the other of the cylinders in excess amounts.

To this end a lubricating device is provided which is adapted to receive a 100 small quantity of oil from the reservoir J and to receive and entrap and thereupon to discharge the oil into the feed cylinder B.

In the preferred embodiment of the invention, the lubricating device includes a casing K which is adapted to fit into a bore L in the back head O of the cylinder A,

preferably in the form of a cylindrical bushing having an inlet P by which oil passing from the reservoir J by gravity or air pressure may find its way through the passage 5 Q into the interior of the casing K. An outlet R through the casing K, longitudinally spaced from the inlet P, is adapted to permit the oil from the interior of the casing to flow down through the groove S into the 10 feed cylinder B. Within the casing K a plunger T is adapted to be actuated by air admitted under the plunger T from the air feed cylinder B through a passage U. The plunger T is hollow having a bore V within 15 which a piston W is arranged to slide, the piston W being held centrally between the upper end of the casing K and the bottom of the bore V by resilient means, such as the coil springs Y and Z, the latter spring being 20 above the piston W.

Oil is adapted to be admitted to the bore V from the inlet P through ports b which, when the plunger is in an upward position, also allow the oil to escape from the bore 25 V into the outlet R. Oil in the interior of the casing K above the piston W is permitted to escape into the passage Q through a relatively small port c and thence back to the reservoir J.

30 The operation of the pump is as follows:—When air is admitted into the feed cylinder B, it finds its way through the passage U to the under-face of the plunger T which rises against the compression of the 35 springs Y and Z so as to close the inlet P entrapping the small quantity of oil under the piston W within the plunger T. Since the oil is relatively uncompressible, the lower coil spring Y is not materially compressed 40 while the upper coil spring Z exerts a force tending to force the oil out of the plunger. There is no outlet however for the oil thus entrapped until the plunger T rises to a point at which the ports b register with the 45 outlet R. Thereupon a small quantity of oil within the plunger T escapes through the outlet R into the cylinder B as shown in Figure 2. The plunger T remains in this position while the air pressure within the 50 feed cylinder B is maintained. Upon reduction of the air pressure the plunger T moves downwardly to its normal position as shown in Figure 1 due to the compression of springs Y and Z, whereupon oil again is 55 admitted to the interior of the plunger T by gravity and by suction due to the action of the spring Y against the piston W.

It will be noted that at no time is there 60 communication between the feed cylinder B and the hammer cylinder A, although oil is also supplied from the reservoir J to the interior of the hammer cylinder A. The air actuating the hammer piston D is continuously pulsating and therefore is pumped in- 65 to and out of the reservoir J through the

passage d connecting the hammer cylinder A with the reservoir. The circulation of air into and out of the reservoir J causes a slight amount of oil to be carried into the hammer cylinder A for lubricating the parts 70 associated therewith.

If desired, the drill may be of the automatic rotating type and to this end there may be provided a ratchet e cooperating with the ratchet ring f and having a fluted 75 rifle bar g engaging the rifle nut h in the piston D. The drill may also be provided with a water supply tube j extending from a water head k in the back head O through the hammer piston D into the front head F 80 to feed cleansing water to the hollow drill steel E. The handle o is provided for guiding the drill and for resisting its rotation. A throttle valve of any suitable type may be provided. Preferably, the throttle valve p 85 is adapted to supply air under pressure simultaneously to the hammer cylinder A and the feed cylinder B, the port q cooperating with a port r for admitting compressed air to the feed cylinder only being shown.

The cup leathers H are clamped to the feed piston G by a suitable bolt s having a spacer t to receive a loosely fitting retaining spring u which cooperates with a bushing v rigidly held in the upper end of the feed 90 cylinder B to hold the piston G in its retracted position for convenience in transporting the tool.

We claim:—

1. A rock drill comprising a hammer cylinder, an air feed cylinder, a reservoir adapted to supply oil to both of said cylinders, a lubricating device including a casing having an oil inlet from said reservoir and an outlet to the feed cylinder, a hollow plunger within said casing adapted to be actuated by air from the feed cylinder to receive oil from said inlet, and a piston within said plunger to discharge the oil from said plunger through said casing into the feed 100 cylinder.

2. A rock drill comprising a hammer cylinder, an air feed cylinder, a reservoir adapted to supply oil to both of said cylinders, a lubricating device including a casing having an oil inlet from said reservoir and an outlet to the feed cylinder, a hollow plunger within said casing adapted to be actuated by air from the feed cylinder to receive oil from said inlet, and a spring 105 pressed piston within said plunger to discharge the oil from said plunger through said casing into the feed cylinder.

3. A rock drill comprising a hammer cylinder, an air feed cylinder, a reservoir adapted to supply oil to both of said cylinders and a lubricating device including a casing provided with an oil inlet and an oil outlet, a hollow plunger within said casing adapted to be actuated by air from said feed 115 cylinder.

cylinder and a spring pressed piston within said plunger, said plunger and piston being adapted to trap oil within the plunger upon actuation by air pressure and to eject said oil into the feed cylinder.

4. A lubricator for fluid actuated machines comprising a reservoir, a casing having an oil inlet from said reservoir and an outlet to the machine, a hollow plunger within the casing adapted to be actuated by air under pressure to receive oil from said inlet, and a piston within the plunger to discharge the oil from the plunger through the casing into the machine.
- 10 5. A lubricator for fluid actuated machines comprising a reservoir, a casing having an oil inlet from said reservoir and an outlet to the machine, a hollow plunger within the casing adapted to be actuated by air under pressure to receive oil from said inlet, and a spring pressed piston within the plunger to discharge the oil from
- 20

the plunger through the casing into the machine.

6. A lubricator for fluid actuated machines comprising a reservoir adapted to contain oil for the machine, and an automatic lubricating device associated with said reservoir and adapted to deliver a given quantity of oil to the machine each time motive fluid is supplied to the machine, including a casing provided with an oil inlet and an oil outlet, a hollow plunger within said casing adapted to be actuated by air under pressure, and a spring pressed piston within said plunger, said plunger and piston being adapted to trap oil within the plunger upon actuation by air pressure and to eject said oil into the machine.

In testimony whereof we have signed this specification.

LEWIS C. BAYLES.
FRED M. SLATER.
